Contigo Purity Glass Water Bottle: Announced Oct. 16, 2016. Available from Internet URL:*Primary Examiner* — Jennifer Rivard*Assistant Examiner* — Catherine S Posthauer(74) *Attorney, Agent, or Firm* — Taylor J. Ross(57) **CLAIM**

The ornamental design for a cap with strap for bottle, as shown and described.

DESCRIPTION

This application is related to co-pending application Ser. No. 14/746,965, which are incorporated herein by reference.

FIG. 1 is a top, front and left side perspective view of a cap with strap for bottle showing our new design;

FIG. 2 is a top, rear and left side perspective view thereof;

FIG. 3 is a top plan view thereof;

FIG. 4 is a bottom plan view thereof;

FIG. 5 is a left side elevation view, the right side being a mirror image thereof;

FIG. 6 is a front elevation view thereof; and,

FIG. 7 is a rear elevation view thereof.
